per Products Company, a corporation of Min-
nesota

Application January 14, 1935, Serial No. 1,638

1 Claim. (Cl. 206—44)

Our invention relates to an improvement in containers, particularly adaptable for containing liquids such as oils and the like. These containers are suitably coated to resist any damaging effects, either to the container or to the contained liquid. In preferred form, our containers are provided with opposed transparent portions, by means of which the contents of the liquid may be observed.

10 It is a feature of the preferred form of our container to provide opposed sight windows in the container through which the ordinarily semi-transparent or translucent contents of the container may be readily observed. While it is known that containers having transparent portions have been used previously, we believe that the provision of these portions in opposed relation in combination with containers for liquids is novel. Furthermore, the provision of such windows in 15 a container designed to accommodate liquids necessitates making the windows both liquid-proof and air-proof, so that the contents may not leak out, and so that the liquids may not be permitted to deteriorate from contact with air or cannot 20 oxidize.

In the case of oily products, suitable grease-proofing substances provide a coating over the inner, outer, or both surfaces of the container, and protects the contents of the container from 25 injury from the material of the container; protects the walls of the container from being affected by the contents of the container, and acts to keep the liquid in the container. The grease-proofing material may also be a water-proofing material if desirable and necessary.

These and other objects and novel features of our invention will be more clearly and fully set forth in the following specification and claim.

40 In the drawing forming a part of our specification:

Figure 1 illustrates a side elevation view of a container formed in accordance with our invention.

45 Figure 2 is a cross-sectional view on the line 2—2 of Figure 1, illustrating the manner in which the sight windows may be formed oppositely disposed therein.

Figure 3 is an enlarged cross-sectional view of 50 a sight window, illustrating a manner in which the window is secured in the container.

Figure 4 is a view similar to Figure 3, illustrating another form of connecting means between the transparent window and the container.

55 Figure 5 illustrates another view similar to

Figure 3, showing another form of connector between the sight window and the container.

Figure 6 is a cross-sectional view through the top of another form of container, illustrating the manner of securing the sight window in the 5 top, bottom, or flat side of a container.

Figure 7 is a perspective view, partly in section, showing the sight window illustrated in Figure 6, and the manner in which the window is attached.

Our container A may be of any shape found most suitable for the described purpose. We have shown, for the purpose of illustration, a cylindrical carton; and while we have designed this carton for formation as a container made of 15 cardboard or laminated paper of some sort, we wish to point out that fiber or a metallic wall formation, or combinations of such various materials, may be used if found desirable.

Windows 10 are formed in the container either 20 during the formation of the walls, or after they have been completed. These windows 10 are shown in Figures 1 through 5 in opposed relation in the side wall portion 11 of the container A, and in Figures 6 and 7 we illustrate a window 10 25 formed in a top or bottom 12 or 13 or side of the container. It is understood that the windows 10 are preferably provided in pairs, and each window 10 is provided with an oppositely disposed window.

Either during the process of manufacture, or upon the completion of the container, the side walls 11, top 12, and bottom 13 are coated with an inner coating 14 and preferably with an outer coating 15. This coating may be a grease-proofing substance, a water-proofing substance, or a combination grease and water-proofing substance.

The window which forms the sight opening may be formed of transparent sheeting material 40 such as regenerated cellulose films and rubber derivatives. Such sheeting may be, for example, cellulose hydrate such as Cellophane and the like, sheeting made of cellulose esters such as cellulose acetate, cellulose nitrate and the like; 45 sheetings made of cellulose ethers such as ethyl cellulose, benzyl cellulose and such materials; and also sheeting materials made of albuminoid materials such as glue, casein, albumin and the like.

Each of the sheeting materials mentioned above are given as the principal ingredient forming the film constituent of a suitable mixture which may be formed by resins, plasticizers, solvents, and the like to produce a film possessing 55

the physical properties for the purpose. It is understood that each mixture is, of course, a transparent film when dried.

With particular reference to the drawing, we will now describe the manners in which the windows 10 may be secured in position in the container. Figure 1, and Figure 2 which is a section on the line 2—2 of Figure 1, disclose the manner in which windows 10 are positioned in opposed relationship, so that when the container A is interposed between the eye and a source of light the transparent or semi-transparent liquids within the container may be observed. It is obvious that these windows may also be oppositely disposed in the ends of the container if desired, as suggested in Figures 6 and 7 of the drawing. While but one end of the container is shown in each of these figures, it is to be understood that the ends may be similarly formed, and the contents may be viewed through the container longitudinally as well as transversely as in Figure 1.

In Figure 3 we disclose a window 10 which is inserted in a gasket formed of a soft material which may be readily bent to form a frame extending about the periphery of the window. The transparent sheeting 16 is held in position between a pair of flanges 17 and 18, while flanges 19 and 20 on the outside of the frame contain the edge of the wall of the container. This form of window may be inserted into a container A having a window opening of proper size and shape after the sheeting 16 has been inserted in place in the frame by leaving one flange 19 or 20 extending in alignment with the body portion 22 of the frame, and bending this flange into the position shown after the frame is in position. In this manner, the frame is forced tightly into contact with both the sheeting 16 and with the wall 11 to form a liquid-proof connection.

In Figure 4 we disclose a slightly different form of frame for the window 10. In this modification, the sheeting 33 is engaged between the opposed sides of a U-shaped sheet metal channel having side flanges formed integrally extending from the open ends of the channel and bent back in finished formation into substantially parallel relationship with each other and with the sides of the U-shaped channel. Figure 4 clearly shows the U-shaped channel 24 and flanges 25 and 26 integrally secured thereto. As in the form illustrated in Figure 3, the frame of Figure 4 may be attached in the opening of a formed carton by crimping either the flange 25 or the flange 26 into engagement with the side wall 11 of the container after the frame and enclosed sheeting 33 is positioned in the window opening.

Figure 5 discloses another type of securing means for the window 10. In this modification, the sheet material forming the transparent win-

dow, designated as 27, is secured in position by a sheet metal frame 28 which is substantially S-shaped in cross-section. Two separate channels are thus formed; one of which comprises opposed side members 29 and 30 between which is crimped the transparent sheet 27. The connected opposed side members 31 and 32 are adapted to enclose the adjacent portion of the side wall 11. Obviously, either the frame can be inserted in the window opening in the side wall 11 and the sheet 27 then inserted in position, or the window pane 27 may be secured in the frame and the assembled window then crimped into position to engage the side wall 11.

The window construction illustrated in Figures 6 and 7 is particularly adapted for use with a laminated container made up of three or more layers of material, designated respectively 33, 34 and 35. The center lamination 34 is provided with an opening which is just the same size, or very slightly larger than, the transparent sheet 36. The laminations 33 and 35 are provided with corresponding openings 37 and 38, respectively, which, however, are slightly smaller than the opening in the lamination 34, or than the transparent sheet 36. Accordingly, when the laminations are secured together, the sheet 36 is substituted for the material cut from the opening in the lamination 34, and the laminations 33 and 35 overlap the sheet 36 and are secured marginally thereto by an adhering means, forming a tight joint.

While we have particularly described our construction as having opposed windows, we desire to have it understood that the use of a single window applied in any manner such as has been described is also a part of our invention.

In accordance with the patent statutes, we have described the principles of our invention, and while we have endeavored to set forth the best embodiments thereof, we desire to have it understood that this is only illustrative of a means of carrying out our invention, and that obvious changes may be made within the scope of the following claims without departing from the spirit of our invention.

We claim:

A container for liquids in combination with a filling of semi-transparent liquid, including a substantially cylindrical body of opaque material, and a pair of relatively small opposed sight windows in said body through which a relatively small amount of the liquid may be observed, said windows positioned so that light rays entering one window may be observed through the other window.
